UNITED STATES PATENT OFFICE.

ANTOUN A. SIMAN, OF DETROIT, MICHIGAN.

SHOE-FASTENER.

1,079,521.

Specification of Letters Patent. Patented Nov. 25, 1913.

Application filed January 18, 1909. Serial No. 472,796.

To all whom it may concern:

Be it known that I, ANTOUN A. SIMAN, a subject of the Sultan of Turkey, residing at Detroit, in the county of Wayne and State of Michigan, have invented certain new and useful Improvements in Shoe-Fasteners, of which the following is a specification, reference being had therein to the accompanying drawings.

10 In shoe fasteners of the buckle or clamp type, the edges of the shoe flaps are usually unyieldingly held in closed position, and that for only a comparatively short distance that is defined by the width of the fastening.

This invention relates to a shoe fastener whereby the edges of the shoe flaps are yieldingly forced together throughout their length and whereby the fastener is locked 20 when closed against accidental displacement although adapted to be clasped or unclasped readily without insertion of buckle tongues or the like, and thus being particularly fitted for shoes for people who are 25 crippled and do not have free use of their hands.

The invention consists in the matters hereinafter set forth, and more particularly pointed out in the appended claim.

30 In the drawings, Figure 1 is a view of a high shoe provided with a fastening embodying the invention. Fig. 2 is a view of a low shoe similarly equipped. Fig. 3 is a view in detail of the fastener in open position. Fig. 4 is a view in detail of the fastener partially open, with its members under compression or tension. Fig. 5 is a view in detail of the fastener fully opened.

Referring to the drawings, a flat spring 40 metal plate 1, arched to fit smoothly over the shoe instep, has inturned or inrolled ends 2 which form tubular bearings. A body 3 of a spring wire link is movably secured in each of these bearings, the outer portion being bent transversely to the body into arms 4 with outturned ends 5. The arms are correspondingly curved to correspond to the plate and the links of each plate are so proportioned that when inturned 45 against the latter, they nearly or quite meet at the plate center.

The fastener is secured to a shoe by in-stitching the link ends along the marginal portions of the shoe flaps 6 so that they may turn readily. Where a single fastener 55 is sufficient, as in a low shoe, the links extend the full length of the flap edges beyond the plate. If two or more are necessary, the wires of adjacent links are extended to meet centrally between the plates. 60

The link ends are given a permanent set corresponding to the contour of the respective flap edges, so that when the fastening is closed, the shoe is well drawn together, while the wire temporarily yields to allow the 65 links to be turned as the plate is moved in and out and at the same time there is a certain amount of flexibility along the line of the shoe opening similar to that afforded by conventional lacing. 70

When the links of the opened fastening are inturned slightly as in Fig. 3, and the plate pressed in, the flaps and inner ends of the links come into abutting relation as in Fig. 4, and the curved arms are compressed and the arched plate distended as the parts are forced home, and are restored to normal position as the closed position of Fig. 5 is reached. Thus the parts cannot readily be displaced and are substantially 75 positively locked when closed. The plate may be ornamental, formed to represent a buckle, or be covered with a bow. 80

Obviously, changes in the details of construction may be made without departing from the scope of the appended claim, and I do not care to limit myself to any particular form or arrangement of parts. 85

The device may be readily adapted for use as a fastener for gloves, the light yielding wire readily conforming to the wrist. 90

What I claim as my invention is:

The combination with a shoe having flaps over-lying the upper instep portion, of a fastener comprising an arched spring metal plate, inrolled ends thereon forming tubular bearings and links each consisting of a spring wire journaled between its ends in one of the bearings and bent beyond the bearings into a pair of similarly disposed 95 arms with outturned ends, the arms being 100 curved to fold closely against the underside

of the adjacent plate and proportioned to hold the flap margins in abutment when so folded, the end portions being institched along the marginal portions of the shoe flaps to which they yieldingly conform and in which they turn axially, the plate and arms being so proportioned that the fastener when closed yieldingly compresses the margins of

the shoe flaps together throughout their lengths.

In testimony whereof I affix my signature in presence of two witnesses:

ANTOUN A. SIMAN.
